ELECTRIC CLOCK

Isador Warshawsky, Brooklyn, N. Y., assignor of twenty-eight and one-third percent to Jacob Warshawsky and twenty-eight and one-third percent to Nettie Warshawsky, both of Brooklyn, N. Y.

Application April 27, 1936, Serial No. 76,523

3 Claims. (Cl. 58—38)

The present invention relates to striking electric clocks and more particularly to a novel and improved striking electric clock in which the time train is also used for the direct actuation of the striking mechanism.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, construction, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a front elevation of an illustrative embodiment of the present invention, with the hands and dial removed;

Fig. 2 is a view similar to Fig. 1 but with the parts in striking, rather than silent, position;

Fig. 3 is a vertical section taken on the line 3—3 of Fig. 4;

Fig. 4 is a plan view of the clock;

Figs. 5, 6 and 7 are detailed perspective views of different parts of the mechanism; and

Fig. 8 is a detailed front view of a different form of gathering pallet and pallet disc.

The present invention has for its object the provision of a novel and improved electric striking clock. A further object is the provision of such a clock which is reliable in operation, simple in construction and economical to manufacture. Another object is the provision of an electric striking clock in which no separate striking train is employed and the striking mechanism is directly actuated by the synchronous motor time train. Still another object is the provision of a striking clock in which a rack for controlling the striking mechanism is returned to its normal position by or under control of a constantly rotating part of the time-keeping mechanism.

As embodied, the time-keeping mechanism comprises a synchronous motor 10, secured to the rear plate 11 of the movement, which has an arbor 12, revolving in a clockwise direction at 180 R. P. M., which projects through an aperture in the rear plate. At its extreme forward end arbor 12 carries a driving pinion 13 meshing with and driving a gear wheel 14, which also acts

as the pallet-wheel of a rack-striking means (later described), which revolves at 30 R. P. M. in a counter-clockwise direction. This gear wheel 14 is staked upon an arbor 15, journaled in the plates 11 and 16 of the movement. 5

The arbor 15 carries near its front end a pinion 17 meshing with and driving a gear-wheel 18 which is driven at 3 R. P. M. in a clockwise direction. This gear wheel 18 is staked upon an arbor 19 journaled in the plates of the movement. 10

Staked upon the arbor 19 a little behind gear-wheel 18, is the hammer-actuating wheel 20, which revolves at the same number of revolutions as gear-wheel 18. Arbor 19 also carries near its extreme rear end a gear-wheel 21, meshing with and driving an identical gear-wheel 22, which revolves in a counter-clockwise direction at 3 R. P. M., and is rotatably mounted on stud 23 extending forwardly from the rear plate 11 of the movement. Gear-wheel 22 meshes with and 15 drives gear-wheel 24 which is the seconds-wheel, at 1 R. P. M. in a clockwise direction. Gear-wheel 24 is staked upon a seconds-arbor 25, near its rear end. The seconds-arbor 25 extends from front to rear centrally through the movement, 20 and may carry at its extreme forward end a seconds pointer 26.

Staked upon the seconds-arbor 25 near its mid-portion, is a pinion 27 which meshes with and drives a gear-wheel 28 at 10 R. P. H. in a 30 counter-clockwise direction. Gear-wheel 28 is staked upon an arbor 29 which is journaled in the plates of the movement. Staked upon the arbor 29 near its front end is a pinion 30 meshing with and driving the minute-wheel 31 at 1 R. P. H. 35 in a clockwise direction. This minute-wheel 31 is mounted upon the extreme rear end of a minute sleeve 32 through which the seconds-arbor 25 extends. The minute-wheel 31 is frictionally coupled to the minute-sleeve 32 to drive the latter 40 through a friction washer 34 staked upon the rear end of the sleeve 32 and against which the said minute-wheel 31 is pressed for frictional engagement by a spring washer 33 staked upon the minute-sleeve 32. At its forward end, extending through the front plate, the minute-sleeve 32 carries the minute-hand 35. Staked upon the minute-sleeve 32, somewhat forward of the minute-sleeve washer 36, is a minute-pinion 37, meshing with and driving a dial-wheel 38 50 carrying a dial-pinion 39 which is mounted together with it upon a stud 40 forwardly projecting from the front plate 16 of the movement in the usual manner of clock-dial-work. The dial pinion 39 meshes with and drives an hour wheel 55

41 staked upon an hour-sleeve 42, sleeved over and rotating freely upon the minute-sleeve 32, in front of the minute-pinion 37. At its forward end, the hour sleeve 42 carries the hour hand 44.

5 Staked upon the minute sleeve 32 directly behind the minute pinion 37 is a minute disc 52 larger in diameter than the minute pinion 37. Projecting rearwardly from the minute disc 52, is a pin 50, for setting the striking mechanism 10 in motion at the hour.

The minute sleeve 32 is held in its proper position on the seconds arbor 25, by a washer 54 staked upon the minute sleeve 32 just behind the front plate and a washer 36 staked upon the 15 minute sleeve 32 just forward of the front plate 16, allowing the minute sleeve 32 just a little axial play.

Figure 1 shows the striking mechanism at rest, or when it is not striking the hour. Most of the 20 parts shown are arranged between the front plate and the dial and are hidden from view by the dial 55.

Gear wheel 14 acts as the pallet wheel of a 25 rack-striking train, and carries on its arbor, extending through the front plate, a modified gathering pallet 61. This modified gathering pallet 61 rotates freely on its arbor, and immediately behind it is a pallet disc 62, staked upon the arbor. The pallet disc 62 carries a straight 30 light spring 63, attached by means of a screw 64. This tension spring 63 operatively bears against the gathering pallet pin 65 on the gathering pallet 61, and since the pallet disc 62 is constantly rotating, the tension spring 63 forces the gathering pallet 61 to rotate with it. A small washer 66 staked upon the arbor in front of the gathering pallet 61 prevents it from coming off the arbor.

The snail 70 is fixed upon the hour sleeve 42 in front of the hour wheel 41, and revolves 40 once in twelve hours.

Rack 75 is oscillatably supported on a stud 76 extending forwardly from the front plate, and is provided with an extension piece 77, resting upon the hook 78 of the rack hook 79.

45 The rack hook 79 is oscillatable on a stud 80 projecting forwardly from the front plate 16, and by means of the spring 81, the rack hook 79 is forced upwards against its stop pin 82 extending forwardly from the front plate, thus lifting the 50 rack 75 out of engagement with the gathering pallet pin 65. A pin 84 extending forwardly from the front plate limits the upward movement of the rack 75.

At the lower end of rack 75 is provided an extra 55 tooth 75' which is engaged by the hook 78, but is short enough not to be engaged by the pin 65 as are the other and longer teeth. This short tooth 75' prevents the hook 78 slipping off the rack before the last stroke and thereby producing a false 60 number of strokes.

The hammer arm 90 carrying the hammer head 91 is rigidly attached to the rear prolongation of an arbor 92, journaled in the plates 11 and 16 and extending therethrough, and its purpose is to 65 strike the gong 94 which is suitably mounted. The lever arm 95 shaped as shown, is rigidly attached to the front prolongation of arbor 92 and the extreme upper end of lever arm 95 rests upon pin 96, extending forwardly from the upper part 70 of rack 75. Lever arm 98 is rigidly attached to arbor 92, between the plates of the movement, and engages the teeth of the hammer-actuating wheel 20. When lever arm 95 rests upon pin 96, lever arm 98 is raised out of contact with hammer actuating wheel 20.

Stop pin 100, projecting forwardly from the front plate of the movement, above lever arm 95, limits upper movement of lever arms 95, 90 and 98 attached to arbor 92.

The warning lever 101, whose purpose it is to 5 start the striking exactly at the hour, revolves about the stud 102 extending forwardly from the front plate. Pivoted on the front side of the warning lever 101 by pin 103 is an extension piece 105, shaped as shown having a hooked portion 106, against which the upper end of spring 107 presses. Spring 107 is wound once about a recessed portion of the tube 108, attached to the warning lever 101, where it is fitted over its stud 102, and is wound several times about a screw 109, 15 to fasten its end. The extension piece 105 also has a downwardly projecting stop finger 110, bearing against the warning lever 101. The spring 107 pressing against the hooked portion 106 of the extension piece 105 forces the downwardly 20 projecting finger 110 to bear against the warning lever 101 to force the lever to its position of rest against stop pin 111, projecting forwardly from the front plate.

The rear side of the warning lever 101 lies 25 against the minute-sleeve washer 36, and the front side of the warning lever 101 lies behind the minute disc 52.

Pin 50 extending rearwardly from the minute disc 52, runs clear of the warning lever 101 but 30 bears against the extension piece 105, when in the course of its revolution in a clockwise direction it reaches extension piece 105, thus forcing the warning lever 101 to the left only very shortly before the hour.

The warning lever 101 has also a projecting finger 122, the purpose of which is to force the rack hook 79 downwardly and to the left, shortly before the hour, as will presently be explained.

The top end of the warning lever 101 is formed 40 as a curved projection piece in which a pin 124 is mounted.

All the wheels of the clock are constantly rotating, whether the clock is striking or not, as the single train serves not only as the striking train 45 but also as the time train.

The operation of the striking mechanism may be described as follows:

As the hands approach the hour, the pin 50 in the minute disc 52 forces the extension piece 105, 50 and thereby the warning lever 101, to the left. This causes the projecting finger 122 of the warning lever 101 to force the rack hook 79 downward, against the action of its torsion spring 81, also causing the rack 75 to drop slowly.

At the same time that the warning lever 101 is forced to the left, its upper projecting pin 124 engages the upper end of lever arm 95, and prevents it from dropping with the rack 75.

As the rack 75 slowly drops its lowest full tooth 60 crosses the path of the gathering pallet pin 65, which after reaching its lowest position on the gathering pallet 61 now begins its rotation upwardly. If the gathering pallet pin 65 engages the tip of the lowest full tooth of the rack, its 65 rotation is momentarily stopped, but the flexible tension spring 63 on the rotating pallet disc 62, bearing against the gathering pallet pin 65 turns about it, until it reaches a position to the right of the gathering pallet pin 65, and forces it to the 70 left, out of contact with the tip of the lowest full rack tooth allowing the further rotation of the gathering pallet 61.

If the gathering pallet 61 were staked upon its arbor, and the gathering pallet pin 65 engaged the 75

tip of the lowest full rack tooth, the clock would stop running, as the gathering pallet pin 65 would not be able to travel past the tip of the lowest full rack tooth.

Usually the gathering pallet pin 65 does not engage the tip of the lowest full rack tooth, but slips past it, no compensating movement of the tension spring 63 being necessary.

The possibility of the gathering pallet pin 65 engaging the tips of the other rack teeth is very remote, since these teeth cross the path of the gathering pallet pin 65 quickly, but if it should occur it is taken care of by the compensating movement of the tension spring 63.

As the rack hook 79 is forced lower and lower, its hook 78 slips from underneath the extension piece 77 of the rack 75 and then from underneath the lowest full rack tooth, and the rack 75 drops until the rack feeler 130 falls upon one of the steps of the snail 70.

The constantly rotating gathering pallet pin 65, on its travel toward the rack teeth, engages one of the teeth of the rack 75 (depending upon which step of the snail the rack feeler 130 has fallen); lifting the rack for a distance of one tooth, but on its travel away from the rack teeth, the rack feeler 130 again drops upon the snail 70. The rack is not raised upwardly tooth by tooth, because the hook 78 of the rack hook 79 has been forced a short distance to the left of the rack teeth (and thus out of contact with them) by the projecting finger 122 of the warning lever 101. This continues for a minute or so (depending on speed of operation of the parts), until exactly at the hour, 35 the pin 50 in the minute disc 52 passes the tip of the extension piece 105, allowing the warning lever 101 to be suddenly forced back towards its position of rest, against stop pin 111, by means of spring 107. This causes the upper pin 124 of warning lever 101 to move out of supporting contact with the top part of lever arm 95, allowing the lever arm 95 to drop, until lever arm 98 makes contact with the teeth of the hammer-actuating wheel 20. The rack hook 79, under the force of its torsion spring 81, is now forced to the right, and the hook 78 engages the rack teeth, and the rack 75 is now lifted by tooth by tooth, by means of the gathering pallet pin 65 and the resilient effort of rack hook 79. Each time that the gathering pallet pin 65 and the rack hook 79 raise the rack one tooth, a tooth of the hammer actuating wheel 20 passes out of contact with the lever arm 98, causing this lever arm to fall towards the next lower tooth of the wheel, thus causing the hammer-head 91 to 55 strike the gong 94. A pin 119, radially mounted in stud 92' in front of plate 16 has an inwardly turned end 120 projecting through a slot 121 in the plate to limit the movement of hammer arm 98 just before the head 91 strikes the gong 94. 60 The elasticity of arm 98 provides the proper striking action.

In order to secure this synchronism between rise of the rack of one tooth and striking of the gong, on each revolution of the gathering pallet pin 65, a tooth of the hammer-actuating wheel 20 passes by the lever arm 98. Since the pallet wheel 14 makes 30 R. P. M. and the hammer-actuating wheel 20 makes 3 R. P. M., the latter wheel has 10 teeth.

After the lowest full tooth of the slowly rising rack 75 has been engaged by the hook 78, the hook slips under the extension piece 77 of the rack 75, and under the force of its torsion spring 81 the rack hook 79 jumps upward until it strikes against its stop pin 82, lifting the rack 75 to its position of

rest out of engagement with the gathering pallet pin 65. At the same time, the pin 96 on the upper part of the rack 75 raises the top part of lever arm 95, so that lever arm 98 is raised above and out of contact with the teeth of the hammer-actuating wheel 20, thus preventing further striking of the gong 94 by the hammer-arm 90.

It is apparent, therefore, that the gong is struck once for each full tooth that the rack is raised, and the strokes are controlled in number by the snail 70. If it is four o'clock the gong is struck four times, if it is ten o'clock, the gong is struck ten times, etc.

It has been stated above that for a minute or so before striking of the hour occurs, the rack 75 is alternately lifted from and dropped upon the snail 70, for a distance of one tooth, by the rotating gathering pallet pin 65. Exactly at the hour, the rack hook 79 moves to the right and engages the rack teeth. It is apparent that if the rack hook engages the rack teeth when the rack happens to be raised one tooth above the snail, the rack hook will engage one tooth less, than if it engaged the rack teeth when the rack were resting on the snail. This would cause inaccuracies in striking the hour.

To assure correct striking, it is necessary that the rack hook 79 engage the rack teeth when the rack is resting on the snail 70. The rack hook must therefore engage the rack teeth when the gathering pallet pin 65 is not engaging the rack teeth. For this purpose there is provided a lever 140 shaped as shown in Figs. 1 and 2, pivoted at 141, on the front side of the warning lever 101, with its stops 142 and 143 forwardly projecting from the warning lever 101, and a pin 145 forwardly projecting from the front plate, slightly above the pallet disc 62. A light spring 134 serves to press the lever 140 downwardly against stop 142. When the striking mechanism is at rest, as shown in Figure 1, lever 40 bears against its stop 142.

Shortly before the hour, when the warning lever 101 is forced to the left, face 140 of lever 140 finally reaches pin 145 and slides upon it until the curved nose is reached, and then face 148 of lever 140 is reached. Face 150 is then reached, and finally face 151, a slight distance to the right of face 150, when the warning lever 101 has forced the rack hook 79 to its extreme left position.

The lever 140 is now between the rack hook 79 and the pallet disc 62 as shown in Fig. 2. A pin 153 extends forwardly from the pallet disc 62 and is located near its rim, some distance behind the free end of the tension spring 63, in reference to the direction of rotation of the pallet disc 62.

The constantly rotating pallet disc pin 153 during a part of its circular path now bears against face 148 and forces lever 140 slightly upward, once every revolution.

Exactly at the hour, the warning lever 101 moves to the right, carrying lever 140 with it, allowing the rack hook 79 to move toward the right on its way to engage the rack teeth. Face 151 of lever 140 slides upon pin 145 until face 150 strikes pin 145 and cannot move past it, thus holding the warning lever 101 against movement to the right, and the rack hook 79 in its movement to the right, before it has engaged the rack teeth. Face 150 cannot move past pin 145, until the pallet disc pin 153 in the course of its revolution, reaches face 148 of lever 140 and raises the lever slightly upward, so that face 150 slides above pin 145. Face 148 and the curved nose of lever 140 slide upon and past pin 145 as the

warning lever 101 moves to the right until it reaches its stop-pin 111, carrying lever 140 with it.

This allows the rack hook 79 to engage the rack teeth and the rack is lifted, tooth by tooth, as already described above.

The operation of lever 140 insures that the rack hook 79 engages the rack teeth when the rack 15 is resting upon the snail 70, because at the moment when the pallet disc pin 153 reaches face 148 of lever 140 to release the lever, the gathering pallet pin 65 is out of engagement with the rack teeth, and therefore cannot raise the rack 15 above the snail 70.

Stop 143 on warning lever 101 limits the upward movement of lever 140.

If the hands of the clock are turned counter-clockwise, as when setting to correct time, the pin 50 in the minute disc 52 is turned counter-clockwise. Pin 50 causes the pivoted extension piece 105 to turn against the force of its spring 107, its downwardly projecting stop finger 110 moving away from the warning lever 101, without moving the warning lever. When the pin 50 passes the tip of the extension piece 105, the extension piece jumps back to its normal position on the warning lever 101, under the force of its spring 107, the downwardly projecting finger 110 of the extension piece 105 bearing against the warning lever 101.

Therefore, when the hands are set backward, no striking occurs, and the mechanism is not damaged or subjected to undue strains.

The pallet disc 62 is preferably so fixed upon its arbor, in relation to the hammer-actuating wheel 20, that the lever arm 95 will be ascending when the rack hook 79 jumps upward after engaging the lowest tooth on the rack, raising the rack 15 to its position of rest, and that a stroke of the gong 84 precedes a rise of the rack of one tooth, and not vice versa. If a stroke of the gong follows a rise of the rack of one tooth, the rack hook 79 after engaging the lowest tooth of the rack 15, would jump upward, raising the rack, which would prevent the further descent of lever arm 95 and thus the final stroke of the gong, and the striking at the hour would be inaccurate.

In Figure 8 of the drawings is disclosed a form of gathering pallet and pallet disc in which the tension spring 163, secured to the pallet disc 62 by means of a screw 164, is shorter in length and its relation to the gathering pallet pin 65 is somewhat different than that shown in Figures 1 and 2 of the drawings. The manner of operation of this form of gathering pallet and pallet disc however, remains exactly the same as for the form disclosed in Figures 1 and 2 of the drawings.

The invention in its broader aspects is not limited to the specific mechanisms shown and described but departures may be made therefrom within the scope of the accompanying claims without departing from the principles of the invention and without sacrificing its chief advantages.

What I claim is:

1. In an electric clock driven by an electric motor, a striking mechanism comprising a rack, a rack hook to restrain the movement of said rack, a warning lever intermittently actuated by the driving gearing of the clock to make said rack hook inoperative and to allow the rack to fall from its position of rest, and to make said rack hook operative again, a snail cam associated with the hour hand of the clock to limit the fall of said rack, a constantly rotating gathering pallet driven from the clock driving gearing to return the rack to its position of rest, a constantly rotating hammer actuating wheel driven from the clock driving gearing, and a hammer shaft having two arms rigidly attached thereto, and rotating therewith, one arm used for contacting the hammer actuating wheel during striking, the other arm cooperating with the warning lever and rack to control the time of engagement of the first mentioned arm with the hammer actuating wheel.

2. In an electric clock driven by an electric motor, a striking mechanism comprising a rack, a rack hook to restrain the movement of said rack, a warning lever intermittently actuated by the driving gearing of the clock to make said rack hook inoperative and to allow the rack to fall from its position of rest, and to make said rack hook operative again, a snail cam associated with the hour hand of the clock to limit the fall of said rack, a constantly rotating gathering pallet member driven from the clock driving gearing to return the rack to its position of rest, a constantly rotating hammer actuating wheel driven from the clock driving gearing, a hammer mechanism, and means including a correcting member movably attached to the warning lever and co-operating with the gathering pallet member to ensure the engagement of the rack hook with the rack at the end of the warning period when said rack is resting upon the snail.

3. In an electric clock driven by an electric motor, a striking mechanism comprising a rack, a rack hook to restrain the movement of said rack, a warning lever intermittently actuated by the driving gearing of the clock to make said rack hook inoperative and to allow the rack to fall from its position of rest, and to make said rack hook operative again, a snail cam associated with the hour hand of the clock to limit the fall of said rack, a constantly rotating gathering pallet member driven from the clock driving gearing to return the rack to its position of rest, a constantly rotating hammer actuating wheel driven from the clock driving gearing, a hammer mechanism, said gathering pallet member consisting of a member staked on its arbor driving another member freely rotatable on said arbor by suitable elastic means, the latter member containing the gathering pallet pin, said elastic means preventing arrest of rotation of the gathering pallet pin by the tips of the rack teeth.

ISADOR WARSHAWSKY.
